UNITED STATES PATENT OFFICE.

CLAY L. HOFFMAN AND WILLIAM E. STONER, OF PORTSMOUTH, OHIO.

SAFETY METALLIC RAILROAD-TIE.

1,114,357.

Specification of Letters Patent. Patented Oct. 20, 1914.

Application filed December 30, 1913. Serial No. 809,530.

To all whom it may concern:

Be it known that we, CLAY L. HOFFMAN and WILLIAM E. STONER, citizens of the United States, residing at Portsmouth, in the county of Scioto and State of Ohio, have invented certain new and useful Improvements in Safety Metallic Railroad-Ties; and we do hereby declare the following to be a full, clear, and exact description of the invention, such as will enable others skilled in the art to which it appertains to make and use the same.

An object of this invention is to provide a metallic rail tie embodying all of the desirable characteristics of the ordinary wooden tie, including its resiliency, and one which may be inexpensively manufactured.

Another object is to provide a metallic rail tie consisting of a minimum number of parts so constructed and arranged as to permit the same to be constructed of considerably lighter material than has heretofore been employed for this purpose.

Another object is to provide a tie so constructed as to positively prevent spreading of the rails of the track.

With these and other objects in view the invention consists in the construction and arrangement of parts as are hereinafter specifically set forth in the specification and illustrated in the accompanying drawings, representing an approved and practical embodiment thereof, in which,

Figure 1 represents a perspective view of the tie partly broken away, as applied to use. Fig. 2 represents a transverse sectional view therethrough. Fig. 3 represents a longitudinal central sectional view partly broken away, and, Fig. 4 represents a bottom plan view of the tie partly broken away.

Referring to the drawing more in detail, the numeral 8 indicates a pair of angle bars L-shaped in cross section and arranged oppositely as most clearly shown in Fig. 2. The bases or horizontal portions 10 of the angle bars are formed at their abutting longitudinal edges with a series of interfitting projections and depressions adapted to prevent relative longitudinal movement of these parts. The vertical portions of the angle bars are formed with recesses 11 adapted to receive the base and a portion of the web of the rails 12. It will be understood that the openings 11 for each bar 8 are formed a distance apart, representing

the desired gage of the track to be constructed thereover.

The inner walls 13 of the vertical portion of the angle bars 8 are inclined upwardly toward each other so as to provide a substantial dovetail groove for the reception of the similar shape body of the rail engaging members 14 which are arranged in pairs and suitably secured together by bolts 15. The upper ends of the members 14 are extended a distance laterally of the body and occupy the enlarged upper ends of the recess 11 in the bars 8, and their adjacent faces are shaped (as clearly shown in Fig. 3) to receive and snugly fit the base and web of the contiguous portion of the rail 12. The upper surfaces of the bases 10 of the angle bars are concave when the bars comprising a pair are united, while the bottom faces of the members 14 are plain, thus leaving the space indicated by the numeral 16 in Fig. 2 the purpose of which is to increase the resiliency of the tie.

A pair of angle bars 8 comprising each tie are suitably secured together by bolts 17 and 80 co-operating nuts 18, and it will be understood that the number and position of these bolts may be varied in accordance with the weight and character of the load imposed upon the rails of the track. Springs 19 are 85 positioned over the bolts and between the adjacent walls of the vertical portion of the angle bars 8 and further increasing the resiliency of the tie. In use, it is desirable to set the greater portion of the tie in the railway road bed as in this way the ordinary and objectionable rattling and rumbling incident to the travel of the cars thereover is eliminated.

What we claim is:

1. A railway tie comprising a pair of oppositely arranged angle bars having oppositely inclined inner walls, pairs of rail gripping members having wedged engagement between the inclined walls of said bars, 100 and bolts extending through said bars for simultaneously securing the latter together and securing said rail clamping members in locked position between said bars.

2. A railway tie comprising a pair of oppositely arranged angle bars having oppositely inclined walls, a pair of rail gripping members at each end of said tie having wedged engagement between the oppositely inclined inner walls of said bars, the upper 110

ends of the bars of the gripping members having suitable recesses to receive the base and adjacent portion of a rail, bolts securing each pair of gripping members together and bolts extending through said bars for simultaneously securing the latter together and securing said rail clamping members in wedged position between said bars.

3. A railway tie comprising a pair of oppositely arranged angle bars having locked engagement, the upper faces of the bases of said bars being oppositely inclined, pairs of rail gripping members adapted to receive portions of the rails and contacting

the upper face of the bases of said angle bars at their opposite corners and providing a space between said members and said bases at the medial portion of the latter, and means for securing said bars together and securing the rails of a track to said members.

In testimony whereof we have signed our names to this specification in the presence of two subscribing witnesses.

CLAY L. HOFFMAN.
WILL E. STONER.
